UNITED STATES PATENT OFFICE.

JAMES C. MOBLEY, OF DES MOINES, IOWA.

FEED-CHUTE PLATE FOR HOT-AIR FURNACES.

Application filed April 19, 1926. Serial No. 103,017.

This invention relates to a novel form of feed chute plate used in connection with a warm air furnace.

The prime object of the invention is to provide a simple, durable and efficient feed chute plate for warm air furnaces which serves to prevent the fire pot brick from toppling or falling forwardly or rearwardly.

Another object of the invention is to so construct the improved feed chute plate that it will allow the circulation of air under said plate, thereby serving to increase the longevity of the plate and to promote combustion within the combustion chamber of the furnace.

Further objects of the invention are to so construct the feed chute plate that it may be readily secured to the front plate of the furnace; to provide means extending from the bottom of the plate serving to support said plate above the fire brick to permit the passage of air under the plate, over the top of the brick and into the fire pot of the furnace; so that the inside edge of the plate will rest flush with the inner surface of the fire brick, and so that any accumulation of ashes through the air slots will gradually sift out again and thus leave the circulation free.

The foregoing and such other objects as may appear from the ensuing description are accomplished by the construction, arrangement, location and combination of the several parts hereinafter more fully described, illustrated in the accompanying drawings, and particularly pointed out in the claims appended hereto, it being understood that slight changes in the precise proportions and minor details of construction may be resorted to without departing from the spirit or sacrificing any of the advantages of the invention.

In the accompanying drawings forming a part of this application it will be seen that:

Figure 1 is a cross section taken through the lower portion of a warm air furnace showing the means embodying my invention applied thereto.

Figure 2 is an enlarged detail section through the fire brick and improved feed chute plate.

Figure 3 is an inverted plan of the feed chute plate, removed from the furnace.

Figure 4 is a section taken through the

feed chute plate in the plane of the dotted lines 4—4, Fig. 3, looking in the direction of the arrows, and

Figure 5 is a detail section taken through the feed chute plate in the plane of the dotted lines 5—5, Fig. 3, looking in the direction of the arrows in said Fig. 3.

In the embodiment of my invention as illustrated, it will be seen that the numeral 1 designates the cast iron front of a warm air furnace, 2 the grate bars employed in connection therewith, 3 the fire brick utilized in the construction of the furnace fire-pot, 4 means for supporting said fire brick, and 5 the improved feed chute plate embodying my invention. This feed chute plate 5 forms the base or bottom of the feed opening of the furnace, and is composed preferably of a single piece of suitable metal formed at its outer edge with a plurality of open depending lugs 6 for the reception of suitable securing bolts 7 for firmly fastening the plate to the inner front portion of the furnace shell, said plate extending inwardly and terminating at its inner edge with a downwardly extending flange 8 having a series of notched formations along its lower edge throughout its entire width, the inner face of said extension resting flush and in vertical alinement with the inner face of the fire brick 3. Intermediate the length of this plate 5 are a series of integral tapered depending lugs or extensions 9, serving to always retain the fire brick in their proper place and prevent their forward or rearward movement, and between said series of extensions 9, and the said flange 8, is formed a series of integral depending lugs 10 adapted to contact with the upper end of the fire brick, thereby holding the plate 5 slightly above the upper end of the fire brick, while on the lowermost edge of the flange 8 is formed a series of integral projections 11, coacting with a series of integral projections 12 extending downwardly from the flange 8, said projections 11 and 12 resting in contact with the recessed portion formed in the upper end of the fire brick, thereby forming a series of openings between the lower face of the plate 5 and the upper end of the fire brick for the free passage and circulation of air under the plate and between said plate and fire brick, and into the fire pot as indicated by the arrow in Figs. 1 and 2 of the drawings, thus serving to prevent the burning off and destruction of the

100

105

110

plate from the intense heat of the fire and also assisting the promotion of proper combustion within the combustion chamber of the warm air furnace.

5 It will be perceived that the downwardly extending projections 11 and 12 are so beveled off at 13 that any accumulation of ashes which may form in the air openings will gradually sift back and out again thus freeing the air circulation.

10 Having thus described my invention what I claim and desire to secure by Letters Patent is:—

15 1. A feed chute plate for warm air furnaces consisting of a single piece of metal formed with a depending flange at its inner edge having a series of notches, said flange adapted to overlap a portion of the fire brick of the fire pot wall of a furnace, and said 20 plate having depending lugs adapted to contact with the outer face of said fire brick.

25 2. A feed chute plate of the character described, comprising a single piece of metal formed with a depending flange at its inner edge, a series of notches in the edge of the flange, a series of depending extensions in-

termediate its ends, and a series of depending lugs between said flange and extensions.

3. A feed chute plate for warm air furnaces consisting of a single piece of metal 30 formed with a depending flange at its inner edge having a series of notches, said flange adapted to overlap a portion of the fire brick of the fire pot wall of a furnace, said plate having depending lugs adapted to contact with the outer face of said fire brick, and a series of depending lugs disposed between the flange and the first-named depending lugs.

35 4. A feed chute plate for warm air furnaces consisting of a single piece of metal formed with a depending flange at its inner edge having a series of notches, said flange adapted to overlap a portion of the fire brick of a furnace, said plate having depending lugs 40 adapted to contact with the outer face of said fire brick, a series of depending lugs adapted to contact with the upper edge of the fire brick, and a notched depending flange formed at its outer edge.

JAMES C. MOBLEY.
